UNITED STATES PATENT OFFICE.

HARRY B. HILLS, OF RIVERTON, NEW JERSEY, ASSIGNOR TO STEWARD DAVIT & EQUIPMENT CORPORATION, OF NEW YORK, N. Y., A CORPORATION OF NEW YORK.

BOAT-DETACHING APPARATUS.

1,281,370.

Specification of Letters Patent. Patented Oct. 15, 1918.

Application filed June 23, 1917. Serial No. 176,477.

To all whom it may concern:

Be it known that I, HARRY B. HILLS, a citizen of the United States of America, residing in Riverton, in the county of Burlington, in the State of New Jersey, have invented certain new and useful Improvements in Boat-Detaching Apparatus, of which the following is a true and exact description, reference being had to the accompanying drawings, which form a part thereof.

My present invention consists in improved boat detaching means, *i. e.* means for releasably securing boats to ships' davits, and the primary object of the invention is to provide simple and effective apparatus for the purpose which will be positive in operation, and will insure the simultaneous release of the two ends of the boat regardless of whether the boat is in contact with the water or not, and is but little apt to get out of order during comparatively long periods of disuse, and is comparatively inexpensive to construct.

The various features of novelty which characterize my invention are pointed out with particularity in the claims annexed hereto and forming a part of this specification. For a better understanding of the invention, however, and the advantages possessed by it, reference should be had to the accompanying drawings and descriptive matter in which I have illustrated and described a preferred embodiment of my invention.

Of the drawings:

Figure 1 is a longitudinal section of a ship's boat, provided with one form of my improved detaching apparatus.

Fig. 2 is a partial section on the line 2—2 of Fig. 1.

Fig. 3 is a section on the line 3—3 of Fig. 4.

Fig. 4 is a view taken similarly to Fig. 1, but on a larger scale, and showing a portion only of what is shown in Fig. 1.

Fig. 5 is a view taken at right angles to Fig. 4.

In the drawings A represents a ship's boat of usual construction, having one of my improved boat detaching devices B secured to the stem of the boat, and another one secured to the stern post of the boat. Each of the two detaching devices B, which are identical in construction, comprises a body

part, which is preferably made of steel plate, bent to form a channel, U shaped in cross section, as shown in Fig. 3. Bolts or rivets C passing through apertures formed for the purpose in the bottom wall of the channel serve to secure the member B to the boat stem, stern post or other portion of the boat structure to which the member is secured. A pin or shaft D having its ends secured in the side walls of the member B, forms a pivoted support for a hook E. The latter, when the boat is in its normal suspended position, engages the link or eye J carried by the corresponding davit block and tackle connection.

The hook E is formed with a locking tail E', which normally lies in the channel between the side walls of the member B, and is held in this position by a locking bolt F. The latter is slidingly received at its ends in the slotted guideways B' formed in the side walls of the member B, and is moved up and down in these guideways by means of a connecting rod G and rock shaft H. The latter extends longitudinally of the boat and is mounted in suitable bearings K carried by the boat. The shaft H is provided at each end with a crank pin H' to which the corresponding connecting rod G is pivotally connected. Preferably the locking tail is so shaped as indicated at E³ that it does not tend to cam the locking bolt F out of its normal locking position.

As shown, each connecting rod G comprises an upper yoke portion G', to which the ends of the corresponding bolt F are pivotally secured. Interposed between the ends of the member G' and the outer walls of the member B are washers F³ surrounding the bolt F, and preventing lateral displacement of the latter. Advantageously friction is reduced, and provision made for compensating for wear by surrounding the bolt F with loose fitting renewable sleeve sections F', F², F'. The two sleeve sections F' work in the slots B', and sleeve section F², which is interposed between the two sections F', is engaged by the locking tail E' of the hook E in the normal condition of the apparatus. Each connecting member G also comprises a tubular body portion, which is shown as riveted or otherwise secured at its upper end to the end member G' and connected at its lower end by an adjustable threaded joint to a yoke shaped member G². The ends of the

legs of the latter are connected by a pivot pin G^3 which passes through a collar or bearing sleeve I surrounding the corresponding crank pin H' . A collar H^3 secured to the end of each crank pin H' holds the corresponding sleeve member I on the crank pin H' . At a convenient place, normally in position to be operated by the coxswain, a lever handle H^4 is secured to the shaft H .

10 In the normal condition of the apparatus, the hooks E of the two detaching devices at the opposite ends of the boat are held in operative engagement with the links J by the bolts F which engage the locking tails E' of the hooks E . When it is desired to disconnect the boat from the davit links J , the shaft H is rotated, and the consequent angular movement of the crank pins H' gives sufficient motion to the connecting rods G to 15 carry the bolts F clear of the locking tails E' of the hooks E . This permits the hooks E to swing up and thereby free the links J . To prevent the links J from accidentally 20 passing out of engagement with the hooks E , in case the supporting tension on the links J is released, I may advantageously provide each detaching device with a pivoted keeper L as shown. Each keeper L comprises a 25 portion passing through and rotatably mounted in the side walls of the corresponding member B , and an arm portion L' which is bent to extend into contact with the tip E^3 of the hook E in the normal condition of the apparatus. In this condition the free 30 end of the arm L' rests, and is gravity held against a supporting stud carried by the member B . In this normal condition of the 35 keepers they prevent the links J from being moved out of engagement with the hooks E . When it is desired to disengage the 40 links from the hooks E without turning the latter out of their normal operative position, this may be done by first moving each keeper L upward, after which the links J may be 45 moved down off the hooks E .

The boat detaching apparatus described possesses certain important practical advantages. In the first place the construction is one which lends itself to the manufacture 50 of all portions of the apparatus by which the weight of the suspended boat is supported out of rolled or forged metal rather than cast metal. The relatively long leverage through which the locking bolt F acts to hold the hook E in its normal position minimizes the liability of the apparatus to fail at this point. Furthermore the apparatus can be made at a small labor cost and with a relatively simple shop equipment. The 55 apparatus is highly positive in its action and is of a character to deteriorate relatively slowly under the conditions of use to which it is exposed and there is small likelihood of the apparatus getting out of order. The inherent strength and compactness of 60

the detaching device is such that a single style and size may well be used with boats differing greatly in character and loaded weight. This facilitates standardized construction and reduces the number of devices 70 which must be carried in stock to supply a given trade demand therefor. The apparatus is easily installed with a sufficiently accurate adjustment of the parts. The thermal expansion and contraction of the parts, 75 owing to their shape and disposition, can have no appreciable effect upon the adjustment of the apparatus. The manner in which the unlocking movement is imparted to the bolts F insures ample force for the 80 purpose. The fact that at the beginning of its unlocking movement each connecting arm G is given a slight angular movement about a center coinciding with the center of the corresponding locking bolt F facilitates 85 the operation of the apparatus in case the detaching device is embedded in ice as may sometimes be the case. By arranging the parts so that the eccentric pins are moved slightly past their upper dead centers when 90 the apparatus is in its normal operative condition the possibility of an accidental release of the hooks E is greatly minimized.

With the construction illustrated, the hooks E may readily be released regardless 95 of whether the weight of the boat is water borne to any extent or not, and if in the water, regardless of whether the davit connections are subjected to a towing strain or not.

It will be noted that when, in withdrawing the locking bolt F , the end of the locking tail E' passes the point where its contact with the bolt or roller F^2 is tangential, the weights resting on the hook acting 105 through the end of the tail will exert on the surface of the bolt or roller F^2 a powerful downward thrust which will greatly assist in and insure the complete withdrawal of the bolt, and as the connection to the 110 crank arms H' and shaft H is positive, this action on either locking bolt will aid in the withdrawal of the other.

If desired to make it practically impossible to release the hooks E until the boat is 115 water borne, this may be accomplished by a material deepening of the notch indicated at E^3 in each locking tail E' .

Having now described my invention, what I claim as new and desire to secure by Letters Patent, is:

1. A davit connection comprising a member adapted to be secured to a boat and formed with a channel, slotted guideways formed in the side walls of the channel, a hook pivoted between the side walls of the channel and having a locking tail, and a locking member slidably movable in the slots of the side walls from the position wherein it engages the locking tail to one wherein 130

it disengages said tail, the engagement between the locking tail and the sliding locking member being such that the locking member does not press the tail backward in 5 moving to unlock it.

2. A davit connection comprising a member adapted to be secured to a boat and formed with a channel, slotted guideways formed in side walls of the channel, a hook

10 pivoted between the side walls of the channel and having a locking tail, and a locking member slidably movable in the slots of the side walls from the position wherein it engages the locking tail to one wherein it 15 disengages said tail, said locking member comprising a pin having three rollers mounted on it, the two outer rollers being located in the slots of the side walls and the central roller lying between the side walls.

20 3. A davit connection comprising a member adapted to be secured to a boat and formed with a channel, slotted guideways formed in the side walls of the channel, a hook pivoted between the side walls of the

25 channel and having a locking tail, and a locking member slidably movable in the slots of the side walls from the position wherein it engages the locking tail to one wherein it disengages said tail, in combination 30 with a rock shaft adapted to be secured along the bottom of a boat and having crank pin at its ends, a sleeve on a crank pin and a connecting rod pivotally connected to the sleeve and to the locking member.

35 4. In combination with davit connections adapted to be secured to the stem and stern

of a boat, and comprising pivoted hooks and locking devices for holding said hooks in operative position, a rock shaft adapted to be secured along the bottom of a boat 40 and having crank pins secured to its ends, sleeves secured on said crank pins, and connecting rods pivotally attached to said sleeves and connected to actuate the locking device. 45

5. Davit connections adapted to be secured to the stem and stern of a boat and comprising a member formed into a channel, and having slotted guideways formed in the channel walls, and a hook having a locking tail pivoted in the channel in combination with a rock shaft adapted to be secured along the bottom of a boat and formed with crank arms at its side, sleeves 50 secured on said crank arms, connecting rods 55 pivotally secured to said sleeves and locking slide members movable in the slots of the channel and pivotally secured to the connecting rods.

6. Davit connections adapted to be secured to the stem and stern of a boat and comprising a member formed into a channel and having slotted guideways formed in the channel walls, and a hook having a locking tail pivoted in the channel, in combination 60 with a locking device of cylindrical section adapted to move from locking to unlocking position in the slotted guideways, and lock actuating means positively connected to the locking devices at both ends of the boat. 70
